[57] CLAIM

The ornamental design for a table or similar article, substantially as shown and described.

DESCRIPTION

FIG. 1 is a front perspective view of a table or similar article showing our new design;

FIG. 2 is a rear perspective view thereof;

FIG. 3 is a top plan view thereof;

FIG. 4 is a front elevational view thereof, a view from the rear being substantially identical thereto;

FIG. 5 is a side elevational view thereof, as viewed from the left of FIG. 4;

FIG. 6 is a side elevational view thereof, as viewed from the right of FIG. 4; and

FIG. 7 is a bottom plan view thereof.
